BOILER FEEDER

Llewelyn M. Reed, Devon, Conn.

Application May 13, 1940, Serial No. 334,701

10 Claims. (Cl. 122—456)

This invention relates to a boiler feeder, and has for an object to provide a simple boiler feed system of high thermal efficiency, and also to reduce to a minimum the number of movable parts to thus increase the reliability of operation and decrease cost of installation, operation and upkeep.

Other advantages and objects will be apparent as the description proceeds.

With the foregoing and other objects in view I have devised a construction as illustrated in the accompanying drawings forming a part of this specification. It will, however, be understood that I am not limited to the exact arrangement and construction shown, but that various changes and modifications may be employed within the scope of the invention.

In these drawings:

Fig. 1 is a front elevation of one embodiment of my improved feeding system with parts broken away to more clearly show the construction; and

Fig. 2 is a vertical section through the preferred type of actuator which may be employed with this feed.

The feeder complete and ready for installation consists of the parts shown in the drawings. It comprises an upright torpedo type body or receiver 10 and a hydraulic actuator 11 located outside the receiver. The boiler to which the feeder is connected is shown at 12, but for convenience in illustration and to save space the boiler is shown at considerably smaller scale than the feeder. The steam outlet pipe from the boiler is shown at 13 supplying steam to any use for which the steam is being generated, and the feed water inlet pipe to the boiler is shown at 14. In the present installation this pipe 14 is connected to the lower part of the receiver 10, and connected to the upper part of the receiver is an equalizing and vent line pipe 15 in which is a control valve 16 which is a combined steam and venting valve, the valve being connected by the steam supply pipe 17 to the direct steam supply pipe 13. The upper portion of the pipe 15 extends into the receiver 10 and upwardly within the same as shown at 18 to discharge into this receiver closely adjacent the top thereof. The valve 16 is operated by hydraulic or fluid pressure on a diaphragm 19, and a suitable valve member 20 shifts between upper and lower seats 21 and 22. When the valve is in its lower position on the seat 21 as shown in Fig. 1, the supply of steam from the pipe 17 to pipe 15 is cut off, but the opening through the valve seat 22 is open so that pressure in the pipe 15 may vent through 55

the discharge 23. When the valve member 20 is raised under action of spring 24 to carry it against the upper seat 22 the vent is closed, but steam may flow from the pipes 17 and 13 to the pipe 15 and be supplied to the upper part of the receiver 10.

The upper part of the actuator 11 is connected to the upper part of the receiver 10 by the pipe 25, while the lower part of the actuator is connected by a pipe 26 with the lower part of the receiver 10 through the discharge pipe 14. Within the pipe 26 is a non-return or check valve 27. Feed water is supplied to the pipe 14 from any source of supply through the pipe 28 connected to the pipe 14 and in which is a non-return or check valve 29. Preferably the pipe 28 is offset downwardly as shown at 30 in which offset the check valve 29 is located so that the check valve is always submerged in the water to prevent water hammer. There is also a non-return or check valve 31 in the pipe 14 between the connection of pipe 28 thereto and the boiler 12 to prevent the boiler pressure forcing water in the boiler back into pipe 14. There is a pipe 32 connected to the lower part of the receiver 10 and the upper part of the pipe 15 a short distance below check valve 33 in this pipe 15 which is arranged to prevent backflow from the receiver 10 into the pipe 15. There is also a check valve 34 in the upper part of the pipe 32 to prevent flow from the pipe 15 into the pipe 32.

The actuator 11 shown more in detail in Fig. 2 comprises the body 35 within which is a float chamber 36 enclosing a float 37 guided at its lower end for vertical movements by a rod 38 having sliding engagement in a spider 39 at the entrance to the supply discharge pipe 36. At its upper side the float is connected to a head 40 having a vertical elongated slot 41 in which is a roller 42 mounted in the body 35 against which presses at one side a spring 43 which provides sufficient friction to hold the float in its extreme position until the water level in the chamber 36 is at its maximum or minimum. That is, the coaction of the roller 42 and spring 43 will retain the float in its lowermost position until the water level in the chamber 36 reaches its maximum to operate the float to its uppermost position. After the float has moved to this uppermost position the roller 42 and spring 43 retains it in this position until the water level in the chamber 36 drops sufficiently to permit the float to drop to its lowermost position. These retarding operations are also assisted by a spring pressed ball 44 engaging the end of the lever 45

connected to the float at 46 and pivoted to the body of the actuator at 47. The end of the lever has surfaces 48 and 49 at different angles against which the ball 44 seats. When the float is in its uppermost and lowermost positions the ball is 5 pressed against these surfaces of the lever by the spring 50 tension of which may be adjusted by a screw 51 to control the times of operation of the float.

Lever 45 operates two control valves 52 and 53 which are shown as ball valves normally held on their seats by springs 54 and 55 respectively and may be lifted from these seats by the lever 45 through slidable rods 56 and 57. The valve 52 controls the supply of fluid pressure from a supply pipe 58 to the pipe 59 connected with the pipe 60 which is connected to the casing 61 of the valve 16 above the diaphragm 19. A branch 62 of the pipe 60 leads to the valve 53 from which extends a vent pipe 63. When the float 37 is in its lowermost position as shown in Fig. 2 the vent valve 53 is closed and the hydraulic or fluid pressure supply valve 52 is open permitting supply pressure from pipe 58 to pass to pipe 60 and diaphragm 19 to force valve member 20 downwardly to the position shown in Fig. 1 to close the steam supply pipe 17 and open the vent from the pipe 15 to pipe 23. When the float is in its upper position the fluid pressure supply valve 52 is closed and the vent valve 53 is open permitting the pipe 60 to vent through the pipe 63 thus reducing the pressure on the diaphragm 19 and permitting the spring 24 to shift the valve member 20 against valve seat 22 permitting flow of steam from pipe 17 to pipe 15 and cutting off communication from pipe 15 to vent 23. The check valves 33 and 34 are provided with small vent openings 64 and 65 respectively passing through the valves for venting purposes which will presently be described.

For the best and most efficient operation the arrangement of the piping connections is very important, although of course they may be varied. Also the location of the various check valves is important as well as the type and quality of these valves. Of course the cost of the equipment varies with the type of materials used. The cheapest units are those where standard piping, fittings, etc. may be used with a welded steel receiver, but the best quality of materials should be used in the actuator and the steam supply and vent valve 16.

In operation the receiver 10 is filled through the connection 28 either from a suitable receiver for feed water or from direct lines which convey condensate, makeup water, etc. This water cannot enter the actuator 11 from the pipe 14 because of the check valve 27, but it may flow by pipe 14 into the receiver 10 because the steam pressure to the pipe 15 is cut off by the valve 20 and the pipe 15 is connected to and venting through the pipe 23 and the top of the receiver 10 is venting through the opening 64 in check valve 33. The receiver 10 will receive this feed water until filled to the overflow point 25a where the pipe 25 from the top of the actuator is connected to the receiver. When the water reaches this level it flows through pipe 25 to the float chamber in the actuator 11, and during the short space of time required for the actuator to function, by rising of the float 37 to open the vent valve 53 and close the pressure supply valve 52 and thus permit steam valve 20 to open, water may continue to flow into the receiver 10, sufficient space being provided above the connection 25a so that 75

there will always be a little steam space at the top of the receiver when the steam valve 20 opens. However, the feeder will function even though the receiver is completely flooded with water. Should this happen check valve 33 prevents the feed water passing out pipe 18 and flooding pipe 15. As described, when the water overflows through 25 into the actuator float chamber the float rises and through the operation described opens the steam valve 20 to permit steam to flow from the pipes 13 and 17 into pipe 15 and through 18 into the top of the receiver 10. Thus steam direct from the boiler enters the top of the receiver, and because of the proper design and proportion of the areas of the steam supply pipe and the receiver equalization of pressures in the boiler and the receiver takes place quickly, yet gradually enough to prevent shock. As soon as this equalization of pressures in the boiler and the receiver takes place the water in the receiver flows by gravity through the pipe 14 and outlet check valve 31 to the boiler. This discharge rate will be in direct proportion to the gravity head available and to the piping arrangement between the receiver and the boiler which should be such as to reduce friction to a minimum. Also, the receiver should be located as high above the boiler as possible to get as much gravity head as possible. A tall receiver helps to increase the head and capacity or volume.

As the water flows out of the receiver 10 it also flows out of the float chamber in the actuator 11. However, the resistance through the check valve 27 in the outlet 26 from the actuator provides the necessary delay in emptying the actuator so that the receiver will entirely empty. When the actuator chamber is empty or nearly so the float 37 falls to its extreme lower position allowing the hydraulic vent valve 53 to close and opening the hydraulic or fluid pressure valve 52 thus applying pressure to the diaphragm 19 and shifting the valve 20 to its lowermost position cutting off supply of steam from the pipe 17 and opening the vent from the pipe 15 to pipe 23. Pressure in the receiver 10 is thus relieved through the pipe 15 and the vent through the valve seat 22 until the pressure in the receiver 10 is less than in the feed water supply line 28 at which time water again flows from the feed water supply line 28 into the receiver 10 and the cycle repeats itself as long as and whenever there is water to be handled. The supply of feed water through the pipe 28 is controlled by a suitable feed water regulator (not shown) to automatically maintain the water level in the boiler at the proper point. The preferred form of feed water regulator is shown in my co-pending application Serial No. 348,703.

It is also desirable to have an equalizing pipe line 66 connected with the upper part of the float chamber in actuator 11, and with pipe 15 behind the steam control valve 16. This carries off pressure due to flash in the actuator 11. Without this the actuator might be slow in filling and the body 10 of the feeder become flooded.

The capacity of this feeder will depend on the number of cycles per hour and these will depend upon how quickly the receiver can be filled, how much gravity head is provided, and how good the piping arrangement is. It is very important for most efficient operation that there be a direct live steam line from the boiler to the receiver independent of other lines. The small vent hole through the disc of the check valve 34 is to allow sufficient steam to enter to break the column in the pipe 32 as the water runs from the bottom

of the receiver tank 10. When the steam valve 20 closes and pipe 15 is placed in communication with pipe 23 so as to vent through this pipe when the water level in the pipe 32 and the tank 10 reaches the lower end of this pipe, pressure in the tank 10 will blow off through the pipe 32 carrying out air and free oxygen through the pipe 32 to the venting pipe 15. Also, the small vent 64 in the check valve 33 permits venting of air from the very top of the receiver. This permits complete venting of receiver 10 by the time water flowing in through pipe 28 floods the bottom connection of pipe 32. This is important because in normal operation this equipment handles water far above the boiling point at atmospheric pressure, and vapor pressure would retard the filling process. The orifice 64 should be about one quarter inch in diameter in a one inch check valve. The pipe 32 gives very rapid reduction of pressure in tank 10 and also rapid venting of air which, because of its weight, would not be vented through connection 18. The lag between fillings of tank 10 is thus greatly reduced giving more rapid action and increasing the boiler feeding capacity of the device. In other words the purpose of pipe 32 is to permit discharge of the greater bulk of the gases under pressure in receiver 10 at the end of the cycle of operation, thereby removing a large percentage of the air which, due to its relative weight, is at the lower part of receiver 10, and is thus for de-aeration. In prior devices feeding boilers by a similar method discharge takes place through a connection similar to pipe 18 or near the top of the equalizing receiver, and therefore the air expands with the water vapor and only a small percentage of it is actually removed. Finally the accumulation of air or oxygen becomes so great that a certain quantity is captured by the water being discharged to the boiler. With pipe 32 the air or oxygen being the heavier of the two elements is really blasted or forced out of the lower part of receiver 10 by the force of the steam above. The orifice 65 in the check valve 34 is preferably relatively small, as a rule not over $\frac{3}{16}$ " or just enough to allow equalization of steam pressure in pipe 32 so water will flow out of the same when it flows out of receiver 10. This orifice should not be a large one, and the check valve at this point prevents extreme commotion, particularly at a time when the water in receiver 10 is below the boiling point, and this occurs at starting up periods and when new steam is turned on new equipment and slugs of cold return water come through. As the overflow from the receiver 10 when it fills through the pipe 25 is to an actuator which is in a separate vessel it gives rapid action which would not be possible if the actuator were in the receiver. The actuator 11 and steam valve 16 control shown are important as insuring positive operation of the steam valve, and also insuring substantially complete filling and emptying of the receiver on each cycle thus giving maximum capacity.

The cross sectional area of the receiver 10 is relatively small with respect to that of the steam supply pipe 15 to thus reduce the rate of surface condensation, and because of this giving much more rapid equalization of pressures in the receiver and the boiler permitting the use of smaller steam supply pipes and requiring much less steam for operation. For effective operation it has been found that a one inch steam supply pipe is sufficient for a ten inch diameter cylindrical tank 10. The relatively small cross sectional area of re-

ceiver 10 to the area of discharge pipe 14 is also important as it permits rapid discharge with little tendency to swirl, which would both retard discharge and create a funnel which would entrain air, and thereby carry it into the boiler.

To get the highest thermal efficiency in boiler feeding, which is a large step toward heat balance in a steam plant, the hottest water available must be used for feeding, and of course the right quantity must be fed to meet the load demands, and the problem of heat balance in the boiler feed system itself is very important. This system when properly applied to a steam plant will be very efficient as compared with other systems because the only thermal loss will be that due to radiation and this quantity will depend upon the sort of insulation employed for the various pipes and receiver tank. And whereas by other methods of boiler feeding from 2 to 8 percent of each boiler's generated energy is expended solely for feeding the makeup water to it, this system does not use over one-half of one percent of each boiler's generated energy. The upkeep cost is very low as compared with pumps and other similar apparatus, and the energy expended in pumping to overcome friction in the pump itself and to force the water against boiler pressure and against excess pressure for feed regulation does not enter into the problem of feeding by this improved system. The loss of this energy is a complete waste, and there is a material saving of maintenance cost of this system over such systems as employ pumps and similar apparatus. This improved system is fully automatic, safe and dependable. The design of this system is so flexible that the right size unit or size and number of units can be installed at a very reasonable cost.

As previously suggested this improved system includes in addition to this feed water system a feed water regulator (not shown) which is either to control the makeup water or to control its discharge to individual boilers whichever may be the most practical, these feed water regulators operating on changes in the water level in the boiler to control the amount of feed water fed to the boiler to maintain this level constant. If the system is used in a plant where there is low pressure condensation available and which would have to be elevated where it may enter the receiver, a suitable type of booster may be employed for this purpose. If the available makeup water in the plant is under sufficient pressure so that it will flow to the receiver another saving is effected. If hot makeup water is available so much the better, but in any case care must be taken to see that all of the feed water which is usually made up of a combination of high pressure returns, low pressure returns and makeup water, is of the highest temperature available, and this can be accomplished by conducting the lowest temperature water or condensate through some heating device, usually a closed type feed water heater, although it is just as practical in many cases to use an open type heater into which the vents from the feeders and boosters are exhausted and from which the heated water is drawn, and elevated to the receiver or receivers. All these points are very important, and if best results are to be obtained each plant should be treated as an individual case and everything be brought into coordination in accordance with the above mentioned factors.

Having thus set forth the nature of my invention, what I claim is:

1. In a boiler feeder, an upright receiver tank

located above the boiler, an outlet connection from the lower part of the tank to the boiler, a steam pipe connection from the steam space in the boiler to the upper part of the tank, a control valve in said steam pipe to connect the steam space with the tank in one position and to vent the steam pipe in its other position, a connection from the lower part of the tank to the steam pipe adjacent the upper part of the tank, a check valve in said connection, an actuator outside the tank comprising a float chamber, a connection from the upper part of the chamber to the upper part of the tank, a connection from the lower part of the chamber to the outlet from the tank, a float in said chamber, means operated by the float to control the control valve, and a feed water supply pipe connected to the outlet from the tank, and check valves in the outlet from the actuator and in the connection from the tank to the boiler.

2. In a boiler feeder, an upright receiver tank located above the boiler, a steam pipe connection from the steam space in the boiler to the upper part of the tank, a control valve in said steam pipe to connect the steam space with the tank in one position and to vent the steam pipe in its other position, a connection from the lower part of the tank to the steam pipe adjacent the upper part of the tank, a check valve in said connection, means dependent on the level of water in the tank to control opening and closing of the steam valve, a feed water connection from the tank to the boiler and a check valve in said connection.

3. In a boiler feeder, an upright receiver tank located above the boiler, a steam pipe connection from the steam space in the boiler to the upper part of the tank, a control valve in said steam pipe to connect the steam space with the tank in one position and to vent the steam pipe in its other position, a feed water connection from the lower part of the tank to the boiler and a check valve in said connection, a connection from the lower part of the tank to the steam pipe adjacent the upper part of the tank, a check valve in said connection having a small vent opening therethrough, and means connected with the tank having operating means dependent on the level of water in the tank for controlling opening and closing of the steam valve to equalize pressures in the tank and boiler when the tank is filled and shut off flow of steam to the tank when the tank is empty.

4. In a boiler feeder, an upright cylindrical receiver tank located above the boiler, an outlet connection from the lower part of the tank to the boiler, a steam pipe connection from the steam space in the boiler to the upper part of the tank, a control valve in said steam pipe, an actuator outside the tank comprising a float chamber, an overflow connection from the upper part of the tank to said chamber, a connection from the lower part of the chamber to the outlet from the tank, a float in said chamber, means operated by the float to control operation of the steam valve, a feed water supply connected to the tank, the cross sectional area of the tank being relatively small with respect to that of the steam pipe to reduce the rate of condensation of steam supplied to the upper part of the tank and also relatively small with respect to the area of the outlet connection from the tank to the boiler, a check valve in the outlet from the actuator, and a check valve in the outlet connection from the tank to the boiler.

5. In a boiler feeder, an upright cylindrical re-

ceiver tank located above the boiler, an outlet connection from the lower part of the tank to the boiler, a steam pipe connection from the steam space in the boiler to the upper part of the tank, a control valve in said steam pipe to control supply of steam to the upper part of the tank in one position and cut off steam from the tank and vent the steam pipe in its other position, a venting pipe connection from the lower part of the tank to the upper part of the steam pipe, an actuator outside the tank comprising a float chamber, an overflow connection from the upper part of the tank to said float chamber, a discharge connection from the lower part of the chamber to the outlet from the tank, a check valve in said connection, a float in said chamber, means operated by the float to control opening and closing of the steam valve, a feed water supply connected to the tank, and a check valve in the outlet connection from the tank to the boiler.

6. In a boiler feeder, an upright receiver tank located above the boiler, an outlet connection from the lower part of the tank to the boiler, a steam pipe connection from the steam space in the boiler to the upper part of the tank, a control valve in said steam pipe, an actuator outside the tank comprising a float chamber, a connection from the chamber to the upper part of the tank, a connection from the lower part of the chamber to the outlet from the tank, a float in said chamber, means operated by the float to control the control valve, an equalizing pipe line connected with the upper part of the float chamber and with the steam pipe connection behind the control valve, a feed water supply pipe connected to the outlet from the tank, and check valves in the outlet from the actuator and in the connection from the tank to the boiler.

7. In a boiler feeder, an upright cylindrical receiver tank located above the boiler, an outlet connection from the lower part of the tank to the boiler, a steam pipe connection from the steam space in the boiler to the upper part of the tank, a control valve in said steam pipe, an actuator outside the tank comprising a float chamber, an overflow connection from the upper part of the tank to said chamber, a connection from the lower part of the chamber to the outlet from the tank, a float in said chamber, means operated by the float to control operation of the steam valve, an equalizing pipe line leading from the upper part of the float chamber to the steam pipe behind the control valve, a feed water supply connected to the tank, a check valve in the outlet from the actuator, and a check valve in the outlet connection from the tank to the boiler.

8. In a boiler feeder, an upright receiver tank, an outlet connection from the lower part of the tank to the boiler, a steam pipe connection from the steam space in the boiler to the upper part of the tank, a control valve in said steam pipe to connect the steam space with the tank in one position and to vent the steam pipe in its other position, a connection from the lower part of the tank to the steam pipe adjacent the upper part of the tank, a check valve in said connection having a small vent opening, a check valve in the steam pipe connection between its connection to the tank and the connection from the lower part of the tank and having a vent opening therein, a feed water supply connected to the tank, and means dependent on the level of water in the tank to control opening and closing of the steam valve.

9. In a boiler feeder, an upright receiver tank, an outlet connection from the lower part of the tank to the boiler, a steam pipe connection from the steam space in the boiler to the upper part of the tank, a check valve in said connection adjacent the tank having a vent opening therethrough, a control valve in said steam pipe to control connection of the steam space to the upper part of the tank in one position and to vent said steam pipe in its other position, a venting pipe connection from the lower part of the tank to the upper part of the steam pipe between the check valve and the control valve, a check valve in said venting pipe having a vent opening therein, an actuator outside the tank comprising a float chamber, an overflow connection from the upper part of the tank to said float chamber, a discharge connection from the lower part of the chamber to the outlet from the tank, a check valve in said connection, a float in said chamber, means operated by the float to control opening and closing of the control valve, and a feed water supply connected to the tank.
10. In a boiler feeder, an upright receiver tank, an outlet connection from the lower part of the tank to the boiler, a steam pipe connection from the steam space in the boiler to the upper part of the tank, a control valve in said steam pipe, an actuator comprising a float chamber, a connection from the chamber to the upper part of the tank, a connection from the lower part of the chamber to the outlet from the tank, a float in said chamber, means operated by the float to control the control valve, an equalizing pipe line connected with the upper part of the float chamber and with the steam pipe connection behind the control valve, a feed water supply connected with the tank, and check valves in the outlet from the actuator and in the connection from the tank to the boiler.
